(57) **CLAIM**

The ornamental design for a jewelry pendent, as shown and described.

DESCRIPTION

FIG. 1 is a perspective view of jewelry pendent in accordance with my new design;

FIG. 2 is a top plan view thereof;

FIG. 3 is a front elevational view thereof;

FIG. 4 is a left elevational view thereof;

FIG. 5 is a rear elevational view thereof;

FIG. 6 is a right elevational view thereof; and,

FIG. 7 is a bottom plan view thereof.

The broken line showing in FIG. 1 is illustrative of environmental structure only and forms no part of the claimed design.
